UNITED STATES PATENT OFFICE.

CHARLES F. CROWDER, OF SEATTLE, WASHINGTON.

AUTOGRAPHIC REGISTER.

1,161,456.

Specification of Letters Patent. Patented Nov. 23, 1915.

Application filed July 6, 1914. Serial No. 849,053.

To all whom it may concern:

Be it known that I, CHARLES F. CROWDER, citizen of the United States, residing at Seattle, in the county of King and State of Washington, have invented a certain new and useful Improvement in Autographic Registers, of which the following is a specification.

My invention relates to improvements in autographic registers and the object of my improvement is to provide an autographic register that shall be adapted to make a carbon copy, upon each of two strips of paper, of a bill of sale or other writing that is made upon successive sections of another strip of paper, and thereupon roll one or both of such two strips together upon one and the same roller, from which roller, when it is completely filled, the said two strips, in the form of a single roll, may be removed and stored as a record, while each of the successive sections of said other strip of paper, upon which is the original written matter, may be torn off successively, each of the same length, as a separate document; and a further object of my improvement is to provide such an autographic register that shall be simple in its plan of construction and be reliable and efficient in its operation.

30 I accomplish these objects by devices illustrated in the accompanying drawings wherein—

Figure 1 is a plan view of an autographic register embodying my invention; Fig. 2 is a view of the same in side elevation; Fig. 3 is a view in vertical cross-section of the same on broken line α , α of Fig. 4; Fig. 4 is a view of the same in vertical section on broken line w , w of Fig. 3; Fig. 5 is an enlarged view of details of the same on broken line y , y of Fig. 4; Fig. 6 is a view in longitudinal mid-section of details of the same; Fig. 7 is a view in elevation of a detail of the same; Fig. 8 is a view in perspective of a detail of the same; Fig. 9 is a cross-sectional view of another detail of the same; Fig. 10 shows parts of the same in vertical section; Fig. 11 illustrates other parts of the same by view partly in end elevation and partly in cross-section and Fig. 12 is a view of such other parts in vertical section on broken line z , z of said Fig. 11.

Like reference numerals indicate like parts throughout the drawings.

55 Referring to Fig. 4, wherein is indicated an inclosing case comprising a bottom plate

14, a rear end wall 15; a front end wall 16 which is hinged at its bottom edge portion to the front end of the bottom plate 14 by hinges, like hinges 17, whereby it may swing outwardly and downwardly from the closed position, its top edge portion being provided with a lock 18 whose bolt 19 may engage with a catch 20 carried by a covering plate 24 hereinafter described in response 65 to the turning of a key 21 to lock said front end wall 16 in its closed position; top covering plates 22, 23 and 24; the covering plate 24 being provided with glass window 25 to permit one to look downwardly into the interior of such inclosing case, while the covering plate 22 is hinged at its front end by pivot screw 26 (as more clearly shown in Fig. 2) whereby its rear end may be raised to gain access to the interior of the rear end 70 of such inclosing case, and the covering plate 23 is fixed to serve as a platen to support paper to be written upon; and side plates 27 and 28 (as seen more clearly in Fig. 3).

The inner sides of the side plates 27 and 28 are provided with oppositely disposed and downwardly projecting rib edged grooves 29, 30 and 31, respectively, the lower end of each of which terminates in an arc 8 of a circle to form a shaft bearing for shafts 32, 33 and 34, respectively, upon which shafts 32, 33 and 34 are mounted rollers 35, 36 and 37 respectively.

Fig. 10 illustrates the plan of construction and the manner of removably mounting the rollers 35, 36 and 37 in which Fig. 10 is a roller, as roller 35, mounted upon a two part shaft 32 one part of which is concentrically fixed within one end of the 9 roller 35 while its other part is slidably and concentrically disposed in the other end thereof to be movable lengthwise, said roller 35 being provided with a hubbed end plate 38 which is fastened by screws to the end 1 surface of the roller 35 through which end plate 38 the movable part of the shaft 32 extends to project its extreme outer end portion against the beveled edge of a hole 39 in the side plate 27.

On the movable portion of the shaft 32 adjacent to the inner side of the end plate 38 is fixed a collar 43 to limit the outward thrust of such movable part of shaft 32 while on such movable part adjacent to the outer surface of the hub of the end plate 38 is disposed a helical compression spring 40

which is confined by a washer 41 and a pin 42 and by the action of such spring 40 between the washer 41 and the hub of the end plate 38 the movable portion of the shaft 32 is normally maintained with its collar 43 against the inner surface of the end plate 38. The outer end of the fixed portion of the shaft 32 projecting from the roller 35 extends within the beveled edges of a hole 44 in the plate 28.

The hole 39 in plate 27 and the hole 44 in plate 28 being each disposed concentrically with the circle which terminates the lower end of the respective one of rib edged grooves 29, the top portion of such grooves 29 at the top edges of the plate 27 and 28, respectively, are beveled outwardly whereby the ends of the shaft 32 may engage with such beveled portions in the operation of placing the roller 35 in its normal position in its bearings such engagement compressing the spring 40 and forcing the movable portion of the shaft 32 inwardly while the roller 35 is being moved downwardly to its normal position whereupon, when it reaches such position, the compression spring 40 acts in an obvious manner to force the opposite ends of the shaft 32 against the beveled portions of their respective holes 39 and 44.

To remove the roller 35 from the inclosing case it is only necessary to lift the roller 35 upwardly, the beveled ends of the shaft 32 coacting with the beveled portions of the holes 39 and 44, in a cam-like manner forces the movable portion of the shaft 32 inwardly against the pressure of the spring 40 to permit the extraction of the roller 35 in an obvious manner.

Projecting outwardly from the outer side of the upper portion of the side wall 28 and extending along the side of one edge of the covering plate 23 is a receptacle adapted to contain a plurality of strips of carbon paper rolled together in a single roll, as the roll 45, of two strips of carbon paper 46 and 47, as indicated in the enlarged view shown in Fig. 5, such roll 45 of carbon paper is frictionally held in its position by a hinged flap 48 in response to the action of the projecting end portion of a helical spring 49 whereby the strips 46 and 47 of carbon paper when pulled may unroll such strips from the roll 45.

Upon the rollers 35, 36 and 37 are disposed rolls 50, 51 and 52 of record paper, upon the paper of roll 50 of which may be printed a series of blank forms to be filled out in manuscript, as, for instance, a blank form of a cash sale of goods.

The record paper of rolls 51 and 52 may each also, if desired, have a like series of forms covering like spaces as are covered by the printed forms on the record paper of roll 50. Disposed beneath the rolls of paper 50 and 51 are hinged friction flaps 53 and 54

which are adapted to maintain a pressure against the underside of the rolls of paper 50 and 51, respectively, by means of the projecting ends 55 and 56 of a spiral spring to keep such rolls of paper from unwinding too freely. A like friction flap 57 actuated by a like spiral spring 58 engages with the underside of the roll of paper 52 for a like purpose. It is to be understood that these flaps are held in position by the weight of the rollers and the paper thereon.

When the rollers 35, 36 and 37, or any of them, are taken out, as for the purpose of putting on a new roll of paper, the friction flaps 53, 54 and 57 are limited in their upward movement by the heads of limit screws 58, 59 and 60, respectively.

Within the interior of the front portion of the inclosing case, as shown in Fig. 4, is disposed in suitable bearings a shaft 61 upon which is mounted fast a roller 62, fragments of which are more clearly illustrated in Fig. 6 wherein it is seen that such roller 62 is provided with a friction spring 63 made of sheet metal of the form shown in Fig. 7 which friction spring 63 is secured in a concentric position on the end surface of the roller 62 to press against the side surface of a gear-wheel 64 to force such gear-wheel 64 against a collar 65 which is provided on the shaft 61 at a point near its end, whereby said gear-wheel 64 may be caused to rotate freely about the shaft 61 except for the resistance due to the spring 63 when the roller 62 is retarded or maintained stationary.

The roller 62 is provided with a longitudinal slot 66 within which the end edges of strips of record paper may be inserted to be secured by the inturned edges 67 of sheet metal rolled into the form of a tube 68, as most clearly shown in Figs. 8 and 9, which tube 68 is thrust freely on to the roller 62 to surround it and upon which tube 68 such strips of paper may be rolled by force of the friction spring 63 in response to a rotation of the gear-wheel 64.

The ends of the shaft 61 are seated in semicircular bearings formed at the junction of two ribs 69 and 70 which project both from the inner side of each of the side plates 27 and 28, the lower ribs 70 serving as a guide in the operation of inserting the roller 62 into its normal position with ends of its shaft 61 in their semicircular seats and the shaft 61 is maintained in its seats by the ends of two levers 71, one on each of the side plates 27 and 28, which are fulcrumed by pivot screws 72 near their central points, such levers 71 being maintained in their normal positions to lock the shaft 61 in its normal position by means of helical compression springs 73, the outer ends of the levers 71 which project through the front wall 16 being depressed to remove the shaft 61 with its roller 62; the upward movement of the outer

ends of the levers 71 being limited by the upper ribs 69.

To cause strips of paper to roll more smoothly on to the tube 68 a friction flap 74 is pivotally mounted on a rod 75 in a position to bear on the rear side of the paper being rolled in response to the action of the ends of a helical spring 76; the backward movement of such friction flap 74 being limited by a rearwardly extended projection 77.

Disposed opposite to each other one on each side of the side walls 27 and 28 within the inclosing case are two suitably guided and vertically slideable shaft supporting members 78 between the top end portions of which extends a roller 79 that is pivotally mounted in bearings in said members 78 thus to adapt said roller 79 to be raised and lowered.

20 The bottom end surfaces of the members 78 rest upon an eccentric shaft 80 which may be actuated by manipulating an arm 81 to raise said members 78 or to permit them to be lowered in response to the action of tension springs 82, as illustrated in Fig. 3.

Directly below the pivots of roller 79 the members 78 are provided with slotted openings through which may freely extend the end portions of the shaft of a roller 83 30 which is pivoted in the walls 27 and 28 whereby the periphery of the roller 83 normally may limit the downward movement of the roller 79 in response to the action of the springs 82 thus to engage with and press together a plurality of strips of record paper to move such paper in response to a rotation of said rollers 79 and 83 which are associated with each other by means of gear-wheels 84 and 85, respectively, which are provided on 35 the like ends of said rollers 79 and 83 and to insert strips of record paper between said rollers 79 and 83 it is only necessary to manipulate the arm 81 to rotate the eccentric shaft 80 to raise the members 78 to lift the 40 roller 79 sufficiently high to admit such paper whereupon the eccentric shaft 80 is turned to let the roller 79 fall to rest on such paper to press against the periphery of the roller 83, in an obvious manner.

50 The gear-wheel 85 on the end of roller 83 is adapted to be rotated by a gear-wheel 86 which is pivoted by a shouldered pivot screw 87 which is screwed into the inner side of the side 27.

55 The gear-wheel 86 is adapted to be rotated by its engagement with a gear-wheel 88 which is mounted on a driving shaft 89 which finds its bearings in the side plates 27 and 28, one end of such shaft 89 extending through the side plate 27 and projecting outwardly therefrom and upon which projecting end portion is freely mounted a gear-wheel 90 disposed upon the hub of a ratchet wheel 91 which is inclosed within the 60 internally grooved rim of a hubbed disk 92

which is pinned to said projecting end portion of shaft 89 and within the space between adjacent teeth of said ratchet 91 are disposed rollers 93 which may engage with the rim of said disk 92 and with the inclined surfaces of said teeth of said ratchet 91 whereby when said gear-wheel 90 is rotated to rotate the ratchet wheel 91 in one direction such rollers 93 may act, in an obvious manner, to rotate the disk 92 but 70 when such gear-wheel 90 is rotated in an opposite direction the disk 93 remains stationary. Figs. 11 and 12, by enlarged views, more clearly show the construction of the relation between the parts comprising the 80 shaft 89, gear-wheel 90, ratchet wheel 91, disk 92 and rollers 93.

Rotary motion may be communicated from the driving shaft 89 to the gear-wheel 64 by the means of an idler gear-wheel 94 85 which meshes with both of the gear-wheels 88 and 64 and which is pivotally secured to the inner side of the side plate 27, as more clearly shown in Fig. 4.

As shown in Fig. 2, the gear-wheel 90 is 90 adapted to be rotated by a pivoted segment 95 of a gear-wheel with which it meshes, said segment 95 being provided with an arm 96 which may be manipulated to swing said segment 95 on its pivot, and when such arm 95 95 is swung toward the right hand, from the position in Fig. 2, throughout the extent of the peripheral distance of such segment 95 then the rollers 93 will serve to lock the ratchet 91 with the rim of the disk 92 to 100 rotate said disk 92 and the shaft 89 upon which it is mounted, but when said arm 96 is released a spiral spring 97, associated with said arm 96 and the pivot of the segment 95, will serve to move said segment 95 105 back to its normal position without rotating the shaft 89 and the disk 92 mounted thereon, thus it is possible upon each manipulation of the arm 96, when it is moved throughout the distance which it may travel, 110 to cause the segment 95 in its movement to actuate the rollers 79 and 83 to move any record paper between them always the same distance for each of such manipulations of said arm 96.

115 To operate the structure thus described, each of the rollers 35, 36 and 37 is provided with a roll of record paper, as rolls 50, 51 and 52, respectively, whereupon the record paper of roll 52 is extended to pass around the rear side of an idler roller 98, thence in a forward direction to lay upon the top of the covering plate 23 which serves as a platen, thence over the periphery of roller 83, thence obliquely downward to connect 120 with the roller 62 and the tube 68, mounted thereon, whereupon one of the strips of carbon paper, as the carbon paper 47 of the roll of carbon paper 45, is extended to lay across such record paper of roll 52 there- 125 130

4

upon the record paper of roll 51 is likewise disposed around the idler roller 98 and extended across such carbon paper 47, thence over the roller 83, thence with the record paper 52 attached to the roller 62 and the tube 68 and thereupon another carbon paper, as carbon paper 46 of roll 45 is extended across the record paper of such roll 51, as shown more clearly in Fig. 5, and thereupon the record paper of roll 50 is extended over idler roller 99, thence over the carbon paper 46 to lay thereon, thence extended over roller 83 to a position where the printed form of such record paper 50 may register with the surface of the covering plate 23 and thereupon the arm 81 is moved to turn eccentric shaft 80 to a position to permit the springs 82 to pull downwardly the roller 79 to press the record papers of rolls 50, 51 and 52 against the roller 83 whereby such rollers 79 and 83 may act reliably to move such record papers when such rolls 79 and 83 are rotated, such rolls 79 and 83 preferably having their surfaces of their peripheries roughened. The covering plate 22 is then swung down into its position to expose through its opening, as shown in Fig. 1, only the extent of the printed form on the record paper of the roll 50 to be written upon, and then when such forms as filled out in manuscript the lever 96 may be swung its full distance from its normal position, whereupon the ratchet wheel 91 will revolve without carrying with it the shaft 89, then such arm is released to permit the segment 95 to return to its normal position and in its travel the ratchet wheel 91, being moved in an opposite direction, will act through the rollers 93 to revolve said shaft 89 with the result that the rollers 79 and 83 will revolve to move all three of the record papers exactly the required distance to present a new printed form while, at the same time, the record papers of rolls 51 and 52, containing carbon imprints of the manuscript on the top record paper of roll 50, will be rolled on to the tube 67 while the record paper of the roll 50 is projected outwardly above the glass window 25 and the printed form with its manuscript may be torn off to be given to a purchaser of goods or otherwise disposed of. Thus for each manipulation of the arm 96 a new printed form may be presented in the exact position required

for it to be properly filled out in manuscript, while a record of such manuscript will be transferred in carbon copy on each of the two record papers of rolls 51 and 52 and such carbon copies on such papers will be rolled upon the tube 68 which, when full, may be removed by unlocking the front end wall 16 and pressing upon the lever 71 to release the shaft 61 from its bearings, whereupon such tube 68 with the paper thereon may be readily removed from the roller 62 and then such tube 68 by reason of its springy nature may be extracted readily from within such roll of papers and such roll of papers may be filed away for future reference.

The tube 68 and the form of the roller 62, with which it is associated, is an important feature of my invention since it provides means for quickly and easily removing the roll of papers wound thereon, another important feature of my invention is the combination of the segment 95, the arm 96, the shaft 89, the gear-wheel 90, the ratchet wheel 91 and the disk 92, whereby the record paper may be moved always a uniform distance always to present the printed form on the record paper in its proper position to fill out in manuscript.

Obviously changes may be made in the form and dimensions of the various parts of my autographic register without departing from the spirit of my invention.

What I claim is:

In an autographic register, a casing provided with a door, ribs on the sides of said casing extending inwardly over the door and provided at their inner ends with substantially semi-circular bearing seats, a paper receiving roller provided with journaled ends removably fitting said seats, levers pivoted to the sides of the casing above the ribs and provided with ends adapted for engagement with the journals of the roll and springs normally holding the journal-engaging ends of said levers against the journals.

In witness whereof, I hereunto subscribe my name this 26th day of June, A. D. 1914.

CHARLES F. CROWDER.
